US0D1040357S

(12) **United States Design Patent** (10) **Patent No.:** **US D1,040,357 S**
(45) **Date of Patent:** **** Aug. 27, 2024**

(54) **TIP FOR HIGH FREQUENCY TREATMENT DEVICE**

(71) Applicant: **WONTECH Co., Ltd.**, Daejeon (KR)

(72) Inventors: **Jong Won Kim**, Seongnam-si (KR);
Jung Hyun Kim, Seongnam-si (KR);
Young Seok Seo, Sejong-si (KR);
Seong Cheol Cho, Daejeon (KR)

(73) Assignee: **WONTECH CO., LTD.**, Daejeon (KR)

(**) Term: **15 Years**

(21) Appl. No.: **29/868,506**

(22) Filed: **Dec. 5, 2022**

(30) **Foreign Application Priority Data**

Nov. 9, 2022 (KR) 30-2022-0045997
(51) **LOC (14) Cl.** **24-01**

(52) **U.S. Cl.** ..... **USPC** **D24/200**; D24/133

CLAIM

The ornamental design for a tip for high frequency treatment device, as shown and described.

DESCRIPTION

FIG. 1 is a top perspective view of a tip for high frequency treatment device;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The portions shown in broken lines are solely for the purpose of illustrating context and environmental structure only and form no part of the claimed design.

1 Claim, 7 Drawing Sheets
